ATTORNEY:

UNITED STATES PATENT OFFICE.

JOHN B. KENISON, OF LYNN, MASSACHUSETTS.

CONDUCTOR FOR STAND-PIPES.

SPECIFICATION forming part of Letters Patent No. 398,735, dated February 26, 1889.

Application filed August 16, 1888. Serial No. 282,898. (No model.)

To all whom it may concern:

Be it known that I, JOHN B. KENISON, of Lynn, county of Essex, State of Massachusetts, have invented an Improvement in Conductors for Stand-Pipes, of which the following description, in connection with the accompanying drawing, is a specification, like letters on the drawing representing like parts.

This invention has for its object to construct a detachable conductor or conveyer for stand-pipes, which are located at convenient places on the sides of the streets, and employed to deliver water from the main pipe to supply water-carts.

In accordance with this invention the conductor or conveyer is carried on the cart, and when it is desired to use the same it is connected with the discharge-nozzle or end of the stand-pipe.

The conductor or conveyer consists of two tapering pipes or cylinders joined together at their larger ends. A suitable strainer is placed within the conductor or conveyer, and also a distributor to break the force of the water. At the upper end of the conductor or conveyer suitable engaging devices are provided, which will be employed to attach the conductor or conveyer to the stand-pipe.

The invention is further described in the specification, and particularly pointed out in the claims.

The drawing shows in side elevation the conductor or conveyer forming the essence of this invention, it being broken out in places to show the parts within it; also the stand-pipe and a portion of the water-receiving tank which is placed on the cart.

The water-tank A is of any suitable size, shape, and construction, it having a water-receiving orifice, a, at the top. The tank A will be placed, as usual, on the cart, (not shown,) and from it suitable pipes will lead, which are provided with sprinklers, also not shown.

B represents an ordinary stand-pipe, commonly located at convenient places at the sides of the street, and as is now used have attached to the discharge nozzle or end a piece of flexible hose by which the water is conveyed or conducted to the water-tank. In practice, where such flexible hose is employed, the water is allowed to drain from the hose after being used, and as a result the street is always

muddy near a stand-pipe. In lieu of the flexible hose, I provide a conductor or conveyer, which consists of two pipes, b B', each 55 tapered from end to end and joined at their larger ends. These pipes may be made of galvanized iron or other suitable material.

A yoke, c, is attached to the screw-threaded collar c', (see dotted lines,) by which the parts 60 are joined together, said yoke having at its lower end a screw-threaded flange, (see dotted lines,) upon which is turned a collar or cap, c². Contained within the yoke and supported by it is a tapering cylindrical strainer, c³, made 65 quite long, and the collar c² contains a foraminous or gauze plate which, it will be understood, forms the bottom of the strainer.

A cross-bar, d, is fixed to the pipe b' above the strainer, it supporting a conical distributing-plate, d', which breaks the force of the water previous to entering the strainer.

The stand-pipe B, at its discharge nozzle or end, has a flange or ring fixed upon it, and a yoke or collar, e, embraces the upper end of 75 the pipe b', from which project laterally ears e', to which are pivoted levers e², the upper ends of which levers are provided with curved engaging-flanges e³, having inclined or tapering vertical extensions e⁴, while the lower end 80 of the levers are acted upon by springs e⁵, normally tending to press the curved flanges e³ toward each other.

The spring-controlled levers e², having the curved flanges or engaging ends, constitute 85 the engaging devices, and in operation, when the conductor or conveyer is lifted, the end of the discharge-nozzle strikes the inclined portions e⁴, thereby spreading the levers, and thereafter the flange 2 acts in a like manner 90 upon the levers, thereby permitting the engaging portions e³ thereof to rest upon the upper surface of the flange 2, holding the conductor or conveyer in proper position.

The lower end of the conductor or conveyer 95 is extended downward into the water-tank. The pipe b of the conductor or conveyer is of sufficient diameter to practically fill the pipes a when not attached to the stand-pipe, and it will be understood that the device is carried 100 about on the cart in this manner.

When it is desired to fill the tank, the cart is driven to a stand-pipe and the conductor or conveyer is lifted, so that the engaging de-

vinces engage the discharge end or nozzle thereof, after which the valve f is opened.

By the device herein described a tank may be filled and the device disconnected without 5 spilling or permitting the water to drain in the street; and, furthermore, by providing the conductor with a strainer obviates the necessity of removing collections from the sprinklers and the pipes leading from the tank, which 10 in practice consumes considerable time.

I claim--

1. The conductor or conveyer herein described, consisting of the tapering pipes $b b'$, joined at their larger ends by the collar c' , the tubular strainer c^3 , distributor-plate d' , independent of and above said strainer, the yoke c , within one of the said pipes and attached to said collar to support said strainer at its ends, and the collar c^2 , attached to the 20 lower end of said yoke and containing a foraminous plate to form the bottom of the strainer, as and for the purpose set forth.

2. The conductor or conveyer herein described, consisting of the tapering pipes $b b'$, joined at their larger ends, the tubular strainer c^3 , supported at either end by a yoke, c , within pipe b , and the plate d' , above said strainer, combined with the engaging device comprising the ears e' , rigidly attached to the end of said pipe, spring-controlled levers e^2 , pivoted thereto, and the projections e^3 , by which to partly inclose and engage the discharge end or nozzle of a stand-pipe, as and for the purpose set forth.

In testimony whereof I have signed my name 35 to this specification in the presence of two subscribing witnesses:

JOHN B. KENISON.

Witnesses:

G. W. GREGORY,
T. L. EMERY.
